UNITED STATES PATENT OFFICE.

JAMES SMITH, OF EDINBURGH, SCOTLAND.

MECHANICAL DETACHABLE HAND AND FOREARM.

Application filed October 6, 1926, Serial No. 139,821, and in Great Britain September 23, 1926.

My invention relates to an artificial mechanical hand which can be locked to an artificial fore-arm, the hand being of the type in which each finger and thumb comprises a spiral spring with a flexible tension wire between the palm and the tips of the finger and thumb and extending along the palm side of each finger and thumb, the fingers and thumb being opened and closed 10 by a flat spring extending from the tip of the finger or thumb to a movable plate arranged within the palm of the hand, the plate being preferably operated by a connecting link from a pivoted ratchet sector 15 which is operated by a wire, and locked in any position by a spring detent controlled by a rod projecting out with the hand, and has for its object to improve the construction and action of such hands.

According to the present invention the usual flat springs, positioned within the spiral springs, secured to the metal finger tips which may be covered with rubber, are held or clamped between two transverse 25 plates, and these plates, together with the flat springs are moved outwards against the action of the spiral spring fingers, on guide rods provided with shock absorbing springs, by the usual connecting link and bell-crank lever. The thumb is provided with the usual flat spring, and the inner end of this spring is connected to a block sliding on a guide rod, said block being connected by a rod to the transverse plates, 30 the rod having an elongated slot formed in it so that a predetermined movement of the fingers takes place before the thumb is operated.

The improved artificial hand is detachable from the artificial fore-arm, in order that another mechanical gripper can be attached to the fore-arm when required. The wrist of the detachable hand is locked to the fore-arm by means of a locking pin engaging a locking plate, and a ball bearing may be formed between the hand and the fore-arm.

In order that my said invention and the manner of performing the same may be properly understood, I hereunto append two sheets of explanatory drawings to be hereinafter referred to in describing my invention.

Figure 1, is a horizontal sectional view 55 of the improved artificial hand. Figure 2, is a longitudinal section through one of the

fingers. Figure 3, is an edge view of the transverse movable members. Figure 4, is a plan view of a combined artificial hand and fore-arm, and Figure 5, is an end view 60 of the locking plate on the fore-arm. In these drawings the same reference numerals are used to mark the same or like parts wherever they are repeated.

Referring to the drawings, 1, designates 65 the shell, and 2, the finger and thumb tips, which may be conveniently made of aluminum, the finger and thumb tips being attached to the shell 1, by spiral fingers 3, and a spiral spring thumb 4. Secured to, 70 and extending from, the tip of each finger and thumb to the shell or palm plate 1, is a flexible inextensible connection 5, which may be of Bowden wire, steel, chain, or cord, or similar material, this flexible connection 5, extending along the palm side of each spiral spring finger 3, and spiral spring thumb 4. The connections 5, prevent the fingers and thumb from bending except towards the palm of the hand. Flat 75 springs 6, extend along each finger, and are secured at one end to the tips 2, of the fingers and at the other end between the pair of clamping plates 7, shown more clearly in Figure 3.

The clamping plates 7, constitute the movable transverse members, being guided for longitudinal movement upon a pair of parallel rods 8, provided with springs 8^a, said rods being secured at one end to posts 90 9, and at the other end to projections 10, projecting from the palm plate 1. The movement of the transverse members 7, towards the fingers cause the flat springs 6, to curve, thereby closing the fingers, whilst the springs 8^a, effect a cushioning action 95 between the clamping plates 7, and the stops 10, and so absorb any shock.

The thumb 4, has a similar flat spring 6^a, which is secured at its inner end to a sliding block 11, mounted on a fixed guide rod 12, said block being connected to one end of a rod 13, the other end of said rod having an elongated slot 14, formed in it, into which projects, and works, a pin 15, 100 on the transverse members 7, so that these transverse members impart a predetermined movement to the fingers before operating the thumb.

The transverse members 7, are actuated by 110 a connecting rod, or link 16, swivelled on the transverse members 7, and having a

swivel connection to one end of a lever 17, pivoted on the palm plate 1. The other end of the lever 17, is connected to a cord or the like 19, which passes over a pulley 20, and which is carried up the arm to any convenient position. The lever 17, is formed with a ratchet sector 21, adapted to be engaged by a spring actuated detent 22, forming one end of a lever 23, pivotally mounted 10 on the palm plate 1. To the other end of the lever 23, there is fixed one end of a rod 24, the other end of which projects through the side of the palm plate 1, where it terminates in a disc 25, between which and the palm plate 1, there is interposed a spring 26.

The inner end of the artificial hand is closed by an end plate 27, from which projects a key-shaped locking pin 28, having an inwardly directed locking pin 28^a. The end 20 of the fore-arm 29 (Figure 4) is also fitted with an end plate 30, having a key-hole aperture 30^a, through which the locking pin 28, is adapted to be passed. The pin 28^a, projecting from the locking pin 28, is 25 adapted to engage any one of an annular series of apertures 31, in the end plate 30, of the fore-arm 29. An annular ball-bearing 32, is also provided between the hand and the fore-arm. This arrangement enables the artificial hand to be detached 30 from the fore-arm, and enables a mechanical gripper to be similarly attached to the fore-arm.

In operation the action of the improved 35 artificial hand is as follows:—The fingers and thumb as shown in the drawings are in their open position, to close them it is only necessary to impart a pull to the cord 19, which turns the lever 17, operates the connecting link 16, which forces outwards the transverse members 7, with the flat springs 6, and 6^a, thus curving the fingers and thumb inwards, to their closed position, against the action of the spiral springs 3, 40 and 4. The fingers and thumb are held 45 at any degree of curvature, and locked, by the spring actuated detent 22. To release the fingers and thumb it is only necessary

to press in the disc 25, against the action of the spring 26, on the rod 24.

What I claim is:—

1. In an artificial hand comprising a palm plate with spiral spring fingers and thumb, flexible wires connected to each finger and thumb, flat springs projecting within each finger and thumb and operated by a movable plate through a pivoted ratchet sector, the combination therewith of movable transverse members between which the flat springs of the fingers are clamped, means 55 for absorbing shock in connection with the movable transverse members, means for operating the thumb from the transverse members, and means for detachably and rotatably connecting and locking the hand to 60 an artificial fore-arm, substantially as set forth.

2. In an artificial hand as set forth in claim 1 the means for absorbing shock in connection with the transverse members consisting of spiral springs interposed between the transverse members and stops, substantially as set forth.

3. In an artificial hand as set forth in claim 1 the means for operating the thumb 75 consisting of a flat spring projecting within and fixed to the thumb, and a sliding block, a connecting rod fixed to said block and to the transverse members, said rod having an elongated slot formed in it, substantially as 80 set forth.

4. In an artificial limb, the combination of a hand, an end plate adapted to be secured on an artificial fore-arm, said plate being provided with a key-hole slot and an annular series of apertures encircling said slot, and a key-shaped locking pin carried by said hand and adapted to pass through said slot, said locking pin having a projection extending parallel with the axis of the hand and adapted to engage any one of said apertures thereby to detachably connect the hand with said plate.

In testimony whereof I have signed my name to this specification.

JAMES SMITH.
